CLAIM

We claim the ornamental design for a rollable television with link, as shown and described.

DESCRIPTION

FIG. 1 is a rear perspective view of a rollable television with link;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a front perspective view thereof.

The broken lines depict portions of the rollable television with link in which the design is embodied that form no part of the claimed design.

1 Claim, 8 Drawing Sheets
